UNITED STATES PATENT OFFICE.

ALBERT J. LEBERT, OF HAZEL, SOUTH DAKOTA.

GRAIN-BINDER ATTACHMENT.

1,252,908.

Specification of Letters Patent.

Patented Jan. 8, 1918.

Application filed May 10, 1917. Serial No. 167,797.

To all whom it may concern:

Be it known that I, ALBERT J. LEBERT, a citizen of the United States, residing at Hazel, in the county of Hamlin, and State 5 of South Dakota, have invented certain new and useful Improvements in Grain-Binder Attachments, of which the following is a specification.

This invention relates to a grain binder 10 attachment and more particularly to an attachment for the sheaf-carrying platform of a grain binder designed to permit a plurality of sheaves to be retained on the platform in a manner that will permit them to 15 be dumped and discharged at the will of the operator.

One of the objects of the invention is to 20 provide a plurality of teeth or tines pivotally mounted above the platform and curved to permit the tines to embrace a number of 25 sheaves so that the sheaves will be retained on the platform, even though the binder is operating over a hilly surface thus retaining the sheaves in position on the platform 30 regardless of the tilted position of the platform.

The invention also aims to provide an attachment of this character that may be 35 easily operated by the operator of the binder 40 through the medium of a simple lever device associated with the retaining means.

A further object of this invention is the 45 provision of a grain binder attachment which consists of comparatively few parts 50 and is simple in construction, but durable 55 and well adapted to withstand the rough usage to which devices of this character are 60 ordinarily subjected.

For a full description of the invention 65 and the advantages and merits thereof, reference is to be had to the following description and the accompanying drawings, wherein is illustrated the preferred form of my invention, in which;

Figure 1 is a side elevation of a portion 70 of a binder showing the attachment applied thereto.

Fig. 2 is a vertical transverse section on 75 the line 2-2 of Fig. 1.

Referring to the drawing, wherein is illustrated the preferred form of my invention, and in which like numerals of reference indicate corresponding parts throughout the several views, the platform consists of the 80 side rails 1 and 2 between which is mounted the usual movable platform 3 constructed

in any preferred manner according to the type of binder upon which the device is used. Spaced from the extreme terminals of the side rails, and rigidly fixed thereto 60 are the upright supports or standards 4 and 5 which are constructed from suitable lengths of angle iron. The upper end of each standard has a portion of one flange of the angle iron cut away and the remaining portion is provided with openings for receiving the trunnions 6 of a rotatable supporting bar 7. Fixed to the bar 7 is a plurality of laterally spaced retaining fingers 8 which are curved as clearly shown by 65 Fig. 1 of the drawing. The terminals of the retaining fingers are curved outwardly from the edge of the platform to prevent the sheaves from being caught on the ends of the fingers when the same are lifted. It will 70 be noted that these retaining fingers form substantially a cage 9 at the end of the platform within which a plurality of sheaves may be received and held until the retaining fingers are raised thus permitting the 75 sheaves to be discharged from the end of the platform.

In order that the fingers may be lifted to permit the discharge of the sheaves, I have provided the bell crank lever 10 pivotally 80 mounted on the pivot bolt 11 carried by the standard 4. The standard is provided with a plurality of openings 12 any one of which may receive the bolt 11 so that the bell crank lever may be adjusted vertically to 85 any desired height. The supporting bar 7 is provided near one end with a yoke 13 to which a rearwardly projecting arm 14 is connected, and the latter is joined to one end of the bell crank lever by a pull rod 15. 90 A connecting rod 16 is joined to the opposite end of the bell crank lever and projects rearwardly to a crank 17 which may be connected to a lever operated near the seat of the operator for the purpose of actuating the 95 connecting rod to swing the bell crank lever on its pivot. When this is done, the pull rod 15 will draw the arm 14 downwardly thus rotating the supporting arm 7 to raise the retaining fingers 8 and permitting the escape 100 of the sheaves in the cage 9.

From the foregoing it will be observed that a very simple and durable grain binder attachment has been provided the details of which embody the preferred form. I desire 110 it to be understood, however, that slight changes in the minor details of construction

may be made without departing from the spirit of the invention or the scope of the claim hereunto appended.

I claim:

- 5 A binder attachment comprising a flat platform having a pair of standards fixed thereto at opposite sides thereof, a bell crank lever pivotally mounted on one of the standards and having each of its arms provided with a plurality of equally spaced apart openings, a connecting rod connected with one of the said openings and adapted for attachment in any of the other openings, for permitting adjustment of the said connecting rod, a pull rod joined to the opposite end of the said bell crank lever in one of the openings therein, a rotatable supporting bar provided with trunnions journaled in the
- 10
- 15

upper end of the said standards, the said bar having a plurality of retaining fingers fixed thereto, and a yoke attached to the said supporting bar and provided with an arm projecting rearwardly from the said fingers and connected to the said pull rods, the said bell crank lever having a pivot bolt, 25 the said standard being provided with a plurality of equally spaced openings any one of which may receive the said pivot bolt to provide an adjustment for the said pull rod and connecting rod.

In testimony whereof I affix my signature in the presence of two witnesses.

ALBERT J. LEBERT.
